UNITED STATES PATENT OFFICE.

FRANK P. GILLESPIE, OF ERIE, PENNSYLVANIA, ASSIGNOR OF ONE-HALF
TO JOSEPH I. TOWN, OF SAME PLACE.

DESIGN FOR A GAS-STOVE.

SPECIFICATION forming part of Design No. 31,537, dated September 19, 1899.

Application filed March 21, 1899. Serial No. 709,979. Term of patent 7 years.

To all whom it may concern:

Be it known that I, FRANK P. GILLESPIE, a citizen of the United States, residing at Erie, in the county of Erie and State of Pennsylvania, have invented a new and original Design for Gas-Stoves, of which the following is a complete specification, reference being had to the accompanying drawing, forming part thereof.

o The figure is a perspective view of a gas-stove embodying my invention.

The leading features of my design consist in the shape and configuration of the stove-top, the legs, and the oven of the stove.

5 As shown in the drawing, the stove-top consists of a rectangular frame B, having a flat vertical outside surface and having a longitudinal bar B' near the center thereof and having transverse bars b between the front 20 B² of the frame B and the longitudinal bar B',

so as to form a rectangular grid, and the portion of the frame B at the rear of the longitudinal bar B' is covered by a plate B³. Legs C C of flat bars, with X-shaped braces C secured between them, are secured to the 25 under surface of the frame B near the ends thereof. The legs C C are also secured together longitudinally by flat bars c c', upon which is secured a rectangular oven D.

Having thus described my invention, what 30 I claim as new, and desire to secure by Letters Patent, is—

The design for a gas-stove, substantially as shown and herein described.

5 In testimony whereof I affix my signature 35 in presence of two witnesses.

FRANK P. GILLESPIE.
